UNITED STATES PATENT OFFICE.

FRANK R. McBERTY, OF EVANSTON, ILLINOIS, ASSIGNOR TO THE WESTERN ELECTRIC COMPANY, OF CHICAGO, ILLINOIS, A CORPORATION OF ILLINOIS.

BUSY-SIGNAL FOR TELEPHONE TRUNK-LINES.

SPECIFICATION forming part of Letters Patent No. 772,897, dated October 18, 1904.

Application filed January 14, 1901. Serial No. 43,259. (No model.)

To all whom it may concern:

Be it known that I, FRANK R. McBERTY, a citizen of the United States, residing at Evanston, in the county of Cook and State of Illinois, have invented a certain new and useful Improvement in Busy-Signals for Telephone Trunk-Lines, of which the following is a full, clear, concise, and exact description.

This invention concerns means for testing lines in telephone-exchanges to determine whether they are free to receive connections. It is designed to give a busy-test indication, preferably a visible signal at one terminal station of a line when the required line is tested and found "busy" at the distant terminal of the line, as in the case of an interoffice trunk-line, to signalize by a visible indication to the answering or A operator that a line called for is found already in use when tested at the receiving or B terminal of the trunk-line.

It is usual in the art of telephony for the B operator, having received a call for connection with a designated subscriber's line terminating before her, and finding the line in use through a prior connection, to insert the terminal plug of the trunk-line through which the line of the calling subscriber has been temporarily extended to her station into a special spring-jack or socket through which a specialized audible test-current is applied to the line, which indicates to the distant operator, and also in some cases to the calling subscriber, that the line wanted is in use; but this practice imposes upon the A operator the necessity of bringing her telephone into the trunk-line to ascertain the presence of the busy indication, and upon the B operator the unnecessary work of removing the terminal plug of the trunk-line from the special "busy-tone" jack.

In devising my improvement I have aimed to avoid the acts of the A and B operators mentioned; to cause the B operator's test of the line called for to display before the A operator a visible signal showing the busy condition of the line, permitting the B operator to replace the terminal plug of the trunk-line in its seat and dismiss the attempted connec-

tion from her attention and enabling the A operator to promptly advise the waiting subscriber. I may thereby secure promptness of service, economy of labor, and diminished length of occupancy of trunk-lines for abortive calls. For this purpose I provide in my invention an instrument connected with the terminal plug of the trunk-line or equivalent conductor at its switching or B terminal responsive to the test-current derived from a busy line, a visible signal at the other, the originating terminal controlled by this instrument, means made active in the response of the instrument for maintaining the display of the signal after the cessation of the momentary testing-current, and other means controlled at the originating terminal for restoring the mechanism to its initial condition in readiness for a test.

A suitable combination of my invention with the mechanism found in the prevailing switching system for telephone-exchanges may be organized as follows: An electromagnet capable of responding to the test-current distinctive of busy lines is connected in a ground branch from the testing-contact, usually the tip, of the terminal plug of the trunk-line at the B station. This magnet actuates relay-contacts, which in turn control a circuit through the trunk-line, which includes a visible signal, as a supervisory signal, at the A terminal of the line, a winding of the magnet being interpolated in the circuit so controlled; and a source of current being applied to the trunk-line at the A terminal of the trunk-line, so that the circuit when closed by the magnet maintains the excitement of the latter as well as the display of the signal. An electromagnetic switch arranged at the B terminal to cut off the normal connections of the trunk-line with this test-indicating magnet during the use of the line for conversation, its actuating-magnet being placed in a local circuit closed in registering contacts of the terminal plug and the spring-jack in which it is inserted, for example, and the "locking-circuit" or device for maintaining the excitement of the testing-magnet after its initial response is

controlled by a suitable switch at the A terminal actuated in breaking the connection there with the trunk-line. If it is desired to utilize the supervisory signal associated with 5 the calling-plug at the A station to indicate the busy test as above suggested, the special circuit applied by the test-indicating magnet to the trunk-line is led through a constantly-operating circuit-controller, which varies the 10 resistance of the circuit to cause the signal to be intermittently displayed in a characteristic manner without rendering the current ineffective for locking the magnet. I will describe this form of the invention more fully 15 in connection with the drawing.

The diagram illustrates two substation-lines entering different central offices, a trunk-line between the offices with the usual associated appliances and the special mechanism of the 20 invention connected with the trunk-line. The circuits and apparatus are well known to telephone-engineers as constituting the central battery system.

The lines from the substations *a* and *b* enter switchboards in the offices A and B, respectively. A trunk-line 12 extends between the offices, ending in multiplied spring-jacks in the switchboard at the A office and in a terminal plug at the B office. Pairs of plugs and 25 their plug-circuits in the switchboard at the A office serve to unite any calling-line with the trunk-line leading to the B office, wherein the line called for can be reached. A central battery *c* for supplying current to excite the 30 substation-transmitters and to operate the visible signals is connected in a bridge of the plug-circuit 34. In the path of current from this source to the called line a supervisory relay *d* is interposed, which controls by means 35 of a shunt a supervisory signal *e* in a local battery-circuit 56, which becomes closed in registering contacts of plug *f* and the thimble of a spring-jack in which the plug is placed. In applying the invention to this system of 40 circuits I provide an electromagnetic switch *g*, a test-indicating relay *h*, and a constantly-operating circuit-controller *i*. The actuating-magnet of the switch *g* is connected in a conductor 7, terminating in the local contact 45 of terminal plug *h* of the trunk-line, through which it is united with the local conductor terminating in the testing of any substation-line with which it is connected. The switch-contacts *g' g''* of the switch control a normal 50 break in conductor 1 of the trunk-line. Switch-contacts *g' g''* control a circuit 8 from the portion of conductor 1 leading to the testing-tip of plug *h*, which traverses one of two windings upon the magnet of relay *h*, a derivation 55 of the circuit being taken through the telephone of the B operator also. The switch-contacts *g' g''* control a conductor 9, leading from conductor 2 of the trunk-line to earth through the circuit-controller *i*. This path 60 last traced also traverses the other winding 65

h' of magnet *h* and is controlled by the relay-contacts of that magnet.

The circuit-controller is permanently shunted by a coil *l* of high resistance, say ten thousand ohms, sufficient to prevent the operation 70 of the supervisory relay *d* when thrown into its circuit. The controller *i* operates to short-circuit this resistance periodically, as twice in a second. The locking-winding *h'* should have sufficient power to hold the armature of 75 relay *h* even when the coil *l* is in the circuit.

In the operation of the system here presented incoming calls reach the A office and are answered by the A operator, who may give the order for the line called for to the proper B operator over an order-wire. The B operator designates a trunk-line 12 to be used in making up the connection, and the A operator immediately links the calling-line with the trunk-line by inserting the mate plug 80 of the one used for answering the call into the spring-jack of the trunk-line. The B operator tests the line called for by applying the tip of the plug *h* to the test-ring of its terminal spring-jack. If the line is in use or busy, 85 a test-current is derived through the test-tip, which flowing to earth through conductor 8 excites test-indicating magnet *h* and draws up its armature. The closure of the contacts of 90 this relay completes a circuit from the central battery at the A terminal of the trunk-line through one conductor 2 of the trunk-line and wire 9, which maintains the magnetization of the relay *h* and brings the supervisory relay *d* under the control of the circuit-controller *i*. The relay *d* when excited closes 95 the shunt about the supervisory lamp *e*, which, it will be noted, was lighted by current in the local circuit completed by placing the plug *f* in the terminal jack of the trunk-line; but 100 through the action of the controller *i* at the B office its excitement is made intermittent, and the lamp is caused to give a pulsating or 105 flickering signal which, being characteristic, constitutes the visible busy-signal. The B 110 operator at the same time hears the click produced in her telephone by the derived test-current and replaces the plug *h* in its seat. The A operator may notify the calling party 115 of the failure to secure the called line and will then remove the plug *f* from the trunk-jack. Severing the connection of battery *c* from the trunk-line deprives the locking-winding *h'* of current and returns the mechanism 120 to its initial position. When the B operator finds the line tested free for the desired connection, she places the plug *h* in the jack of the line wanted. This insertion of the plug closes the local circuit 76, including the magnet *g*, which, being excited, breaks 125 the connection of branches 8 and 9 with the trunk-line and closes the break in the conductor 1, completing the desired electrical circuit between the substations.

The B operator may disconnect the trunk- 130

line from the line called for upon observing the clearing-out signal of the supervisory lamp or she may be furnished with a special disconnection signal controlled by any of the 5 well-known devices.

My invention may be modified or embodied in various forms; but

The features which I claim as new are defined generally in the following claims:

- 10 1. The combination with telephone-lines provided with multiple connection terminals, of a test-circuit and a testing-contact controlling the same, a test-indicating magnet responsive to changes in the electrical condition 15 of said circuit, a "busy-signal" indicator controlled by the magnet, and a "locking" device made active in the response of the magnet for maintaining the busy indication after the cessation of the test-current through the 20 magnet, as described.

2. The combination with telephone-lines, test-contacts associated therewith and means for changing the electrical condition of the test-contacts of a line in making connection 25 with the line, of a testing-contact, a magnet responsive to the test-current derived from the test-contacts, a busy-test signal-indicating device controlled by the magnet, a locking device for maintaining the indication 30 thereof after the cessation of the testing-current, and means for rendering the locking device ineffective, as described.

3. The combination with a telephone-line, test-contacts associated therewith, a test-circuit of the line adapted for closure at one point in making connection with the line and at another point through a testing-tip of a 35 terminal plug of a telephone trunk-line, of a test-indicating magnet responsive to the testing-current connected with the tip, a busy-test-indicating device at the distant terminal of the trunk-line in a circuit controlled by the magnet, a locking-circuit made effective in the response of the magnet adapted to maintain 40 the signal independent of the busy-test current, and a switch at the said distant terminal for breaking the locking-circuit, as described.

4. The combination with telephone-lines and test-circuits and test-contacts thereof, a 50 link conductor, as a trunk-line, and means for connecting a telephone-line therewith at either end, of a testing-tip forming a terminal of the link conductor, a magnet responsive to testing-current, connected with said testing-tip, a test-indicating instrument associated with said tip and adapted to indicate a test-current, another test-signal-indicating device at the distant station in a circuit controlled by said magnet, a locking device actuated by 55 said magnet adapted to maintain the closure of circuit controlled thereby after the cessation of testing-current, and a switch actuated in breaking connection with said link conductor at the distant station controlling the 60 locking device to render it ineffective, as described.

5. The combination with telephone-lines centered at answering and receiving switchboards and test-circuits for said lines, of a 70 trunk-line extending between the switchboards having a plug-terminal at the receiving end, a test-indicating magnet responsive to testing-current connected with said plug and a testing-telephone also connected there- 75 with at the receiving-switchboard, a visible signal at the answering-switchboard and a circuit therefor controlled by said magnet, a locking-circuit for the magnet controlled by the magnet, a switch at the answering-switch- 80 board for breaking the locking-circuit, and an electromagnetic switch at the receiving- switchboard having its magnet in a local circuit closed by the terminal plug of the trunk-line in making connection with another line 85 at the receiving-switchboard, said switch being adapted to break the normal circuits from the test-contact of the plug to the test-indicating devices, as described.

In witness whereof I hereunto subscribe my 90 name this 1st day of December, A. D. 1900.
